LOCK-DOWN SHINGLE

Edward J. Boarini, Chicago, Ill., assignor to Certain-Teed Products Corporation, Ardmore, Pa., a corporation of Maryland

Application May 25, 1950, Serial No. 164,093

3 Claims. (Cl. 108—7)

1

This invention relates to roofing and particularly to asphalt shingles of the interlocking type.

This invention has for its object the provision of a new and improved form and arrangement of shingle by which the lower end portion of each of such shingles on a roof has interlocking engagement with the adjacent shingles so as to prevent the exposed portions of the shingles from being bent up by the wind. My improved shingle is made preferably from flexible prepared roofing material of the type commercially employed in exceedingly large amounts, and it is one of my objects to make my improved shingle of such size and shape as to enable it to be cut readily from a web of roofing felt with very little waste. It is another and related object of my invention to give my improved shingle such conformation as to enable me to produce a roof covering of complete double thickness at all points without undue overlapping of the shingles and with effective protection against the passage of rain through the covering.

Another object of my invention is to provide a form of shingle as above specified in which there shall be a comparatively large nailing zone within which the workman laying the shingles may be able quickly and easily to apply the securing nails in the proper positions without danger that the nails shall be exposed at the outer face of the completed roof, whereby the operation of laying the shingles shall be speeded up so far as is practically possible.

It is still another object of my invention to provide a form of shingle by the use of which a highly decorative type of roof covering shall be obtainable. To this end, I have provided for a variation in the color in the face of my shingle whereby there shall be a band of different colors dividing the exposed face portion of the shingle and thus breaking up the pattern into comparatively small units, with the band parallel to but spaced downwardly a slight distance from and with respect to the lower edges of the shingles at opposite sides, so as to thereby avoid undesired monotony of appearance in the finished roof.

Other and further objects of the present invention will be apparent from the following description and claims and are illustrated in the accompanying drawing which, by way of illustration, shows a preferred embodiment of the present invention and the principle thereof and what I now consider to be the best mode in which I have contemplated applying that principle.

5 Other embodiments of the invention embodying the same or equivalent principle may be used and structural changes may be made as desired by those skilled in the art without departing from the present invention.

In the drawings:

Fig. 1 is a perspective view of a fragmentary portion of a roof embodying my invention;

Fig. 2 is a face view of a strip of felt roofing 10 showing how a series of my improved shingles may be cut therefrom;

Fig. 3 is a cross-sectional view through a plurality of the shingles of the invention arranged in cooperative relationship, the view being taken substantially along the line 3—3 in Fig. 4; and

15 Fig. 4 is a face view of a plurality of my improved shingles in their cooperative relationship on a roof, with parts of some of the shingles broken away, with the outlines of the several shingles completed in dotted lines, and with certain of the shingles provided with surface shading for better distinguishing the several shingles from each other.

20 In the different figures of the drawing, the same reference characters are employed for indicating the various parts. As is clearly shown in Fig. 2, a series of shingles 10 are cut from a strip of roofing felt, with alternate shingles in differential arrangement so as to provide for their production with a minimum of waste material, the several waste parts being indicated by the reference character 13. Each of my improved shingles comprises a head portion 14 and a shank portion 15 of just half as great width as that of the head portion, such shank portion 25 being in centered position transversely with respect to the head portion. In my improved shingle as illustrated, the head portion 14 and the shank portion 15 are of the same size vertically, the distance from the top edge to the bottom edge of the head portion being the same as the distance from the top edge to the bottom edge of the shank portion. At opposite side edges, the shank portion 15 is provided with laterally projecting tabs 16 formed integrally with the shank portion and extending from the lower edge of the shank portion to points positioned at

30 one-third of the distance from said lower edge of the shank portion to the lower edge of the head portion. Each of the tabs 16 is provided 35 at its upper end with an upward projection 17 standing in slightly spaced relationship to the adjacent shank portion, as indicated at 18, the throat or upwardly facing edge of which space 40 is located upwardly from the lower edge in an

amount equal to one-third of the distance between the lower edge of the shank 15 and the lower edge of the head portion 15.

In the form of shingle as illustrated in Fig. 2, the top face of the shingle is in the form of a layer of grit particles applied to the coated strip of felt as the strip is moved lengthwise, such grit particles being applied and pressed into position at the top face of the shingle by the use of any approved form of apparatus, as is well understood in the art. In the embodiment of shingle as shown in Fig. 2, the grit particles are of a selected color but with two narrow zones or bands 18 and 19 of the grit particles of a different color from that of the particles applied at the major portions of the face of the strip. In the preferred form, the band portion 19 on the shank 15 of the shingle and the band portion 18 on the head portion 14 of the shingle are at points located at the same distance from the lower edge of the shank 15 and the upper edge of the head portion 14, and this spacing is somewhat less than the distance between the lower edge of the head portion 14 and the bottom of the throat 17S. The band portion 19 and the band portion 18 on alternate shingles are formed by the same strip of contrasting granules of the basic material, as will be evident in Fig. 2.

In the arrangement as illustrated in Fig. 4, which comprises a number of shingles just sufficient for showing their relationships to each other, there are two shingles 20 and 21 in the first tier with their lower end portions cut away to provide an even bottom edge for the roof, with three shingles 22, 23 and 24 in the next higher tier, two shingles 25 and 26 in the third tier, two more shingles 27 and 28 in the fourth tier, and a single shingle 29 at the top edge of the view. In each tier comprising a plurality of shingles, the head portions are positioned with their side edges abutting, and the tabs 16 and the hooks provided by the projections 17, of the several shingles in each tier, afford a double locking action in that the tabs 16 extend under the shank portions 15 of the shingles of the preceding tier, while such projections 17 project upwardly under the head portions of the shingles of the next lower or preceding tier. The upper edges of the tabs 16, between the shank 15 and the projections 17, serve, of course, as abutment surfaces which engage the lower edges of the head portions of the next lower tier of shingles. This manner of engagement of the several parts and surfaces of adjacent shingles affords an efficient interlock for the lower corners of the shank portions 15.

By such an arrangement carried out through a complete roof, full double coverage is provided throughout the roof, except for the portion of the roof immediately adjacent to the lower edge, and in this lower edge portion of the roof it is, of course, customary to afford a starter or drip strip S of mineral surfaced roofing material, as shown in Fig. 4, which cooperates with the lower tier of shingles to provide double coverage thickness in this portion of the roof. The shape and dimensions of the shingles are such as to insure that the head portions of the shingles of each tier shall abut against each other when the hooks provided by the tab portions of such shingles are positioned for engagement as above described with the angles formed between the straight vertical side edges of the shanks and the straight horizontal bottom edges of the heads of the

shingles of the preceding tier. In the arrangement as shown in Fig. 4, nails 30 secure the shingles firmly in position, such nails being driven through the head portions 14 of the shingles in such position as to be covered by the shank portions 15 of the next higher tier of shingles.

When the hooks of a shingle provided by the tabs 16 and their upward projections 17, and positioned in fairly close proximity to the bottom edge of the shingle, are engaged as above described with the heads and the shanks of the shingles of the next lower tier, such shingle is held very strongly in position so as to prevent its being whipped and bent upwardly by the wind. This is particularly so in view of the fact that in my improved arrangement the lower edge of each shingle lies smoothly on a directly underlying shingle without anything to cause the edge to buckle or bulge upwardly away from the shingle below. The tabs 16 of each shingle and the upwardly directed projections 17 on said tabs are completely covered by the shank portions of the shingles at either side, and each of said tabs and its projections are of such size as to have a strong frictional and mechanical locking hold for resisting withdrawal of the hook from operative position.

In the arrangement of Fig. 4, the band 18 is in every instance concealed, while the band 19 of each shingle is disposed somewhat below the lower edges of the adjacent shingles of the next higher tier, thereby serving to break up the exposed face portions of the several shingles. As a result of this arrangement, my improved roof has a very decorative and distinctive appearance.

In Fig. 1, the several shingles are formed and positioned in accordance with the principles explained in connection with the other figures of the drawing, but the shingles are all designated by the reference character 10 without any attempt to connect up the showing of this figure with Fig. 4 except in a very general way.

While I prefer to employ the form of shingles as shown by my drawing and as above described, my invention is not to be limited thereto except so far as the same may be specifically claimed, it being understood that changes might well be made in the form and arrangement without departing from the spirit of the invention.

I claim:

1. A shingle made from a piece of felt and comprising a head defined by a straight horizontal upper edge and continuous straight vertical side edges, a shank extending below the head in centered position with respect thereto and of just half the width of said head, with the head portions extending transversely beyond the shank defined at their bottom edges by straight horizontal lines and with the shank at its side edges defined by straight vertical lines, and tabs at opposite sides of the shank formed integrally with the shank from the lower edge of the shank to points at a substantial distance from the lower edge of the shank and having upwardly directed projections thereon acting as hooks adapted by engagement with the lower edges of the head portions of a lower tier of similar associated shingles to determine the relative positions of said shingles vertically.

2. A shingle made from a piece of felt and comprising a rectangular head having straight and continuous top and side edges, a shank having parallel vertical side edges and extending below the head in centered position with respect thereto and of just half the width of said head,

said head and said shank being of the same length vertically, and tabs formed integrally with said shank at opposite side edges thereof from the lower edge of the shank to points position at about one-third of the distance from said lower edge of the shank to the lower edge of the head, and having upwardly directed projections thereon acting as hooks adapted by engagement with the lower edges of the head portions of a lower tier of similar associated shingles to determine the relative positions of said shingles vertically.

3. A shingle as specified in claim 2, in which the tabs engage the side edges of the shanks of said associated shingles laid with their heads in edge to edge relationship to each other.

EDWARD J. BOARINI.
